(57) **CLAIM**

The ornamental design for a cosmetic applicator, as shown and described.

DESCRIPTION

FIG. 1 is a top isometric view of a cosmetic applicator in accordance with the new design;

FIG. 2 is a bottom isometric view of FIG. 1 thereof;

FIG. 3 is a front view of FIG. 1 thereof;

FIG. 4 is a top view of FIG. 1 thereof; and,

FIG. 5 is a bottom view of FIG. 1 thereof.

The broken away symbols in FIGS. 1-5 indicate that any portion of the article beyond what is shown forms no part of the claimed design.
